UNITED STATES PATENT OFFICE.

THOMAS WALLACE, OF WABASH, INDIANA.

SLIDE.

1,274,824.

Specification of Letters Patent.

Patented Aug. 6, 1918.

Application filed November 1, 1916. Serial No. 128,952.

To all whom it may concern:

Be it known that I, THOMAS WALLACE, a subject of the King of Great Britain, residing at Wabash, in the county of Wabash and 5 State of Indiana, have invented a new and useful Improvement in Slides, of which the following is a specification.

My invention relates more particularly to an improvement in slides provided as an 10 amusement device for children, and consisting, generally stated, of a slide-section along which the person slides, connected with a ladder at the rear end of the section to enable the user to climb to the top of the slide 15 preliminary to sliding down the latter.

My primary objects are to provide a novel, simple, and economical construction of slide of the general type above stated which shall, by preference, be adapted to be folded 20 into relatively compact condition for storage purposes, a feature which renders it particularly acceptable for use in the house, and other objects, as will be manifest from the following description.

Referring to the accompanying drawings, Figure 1 is a perspective view of a slide constituting the preferred embodiment of my invention, the parts of the slide being shown extended into position for use. Fig. 2 is a 30 view in side elevation of the construction shown in Fig. 1, the parts being illustrated in folded position, as for storage purposes. Fig. 3 is an enlarged broken section at the line 3 on Fig. 1 and viewed in the direction 35 of the arrow, showing a detail of construction of the slide-proper. Fig. 4 is a broken section taken on the line 4 on Fig. 3 and viewed in the direction of the arrow. Fig. 5 is an enlarged broken section taken at the 40 line 5 on Fig. 1 and viewed in the direction of the arrow. Fig. 6 is a view like Fig. 1 of a modification of the slide-proper; and Fig. 7, an enlarged section taken at the line 7 on Fig. 6 and viewed in the direction of the 45 arrow.

Referring particularly to the construction illustrated in Figs. 1 to 5, inclusive, the slide-proper is represented at 10, a platform at the top of the slide is represented at 11, 50 and the latter, provided for permitting the person using the slide to reach the platform 11, is represented at 12. By preference, the slide-proper 10 is formed of side-rails 13—13 spaced apart and held in such spaced relation 55 by means of cross-pieces 14 extending transversely thereof and arranged at intervals

along these side-members, the ends of these cross-pieces fitting into holes in the side-members 13, in which they are secured in any suitable way, as by nails represented at 14^a, and a series of plate-sections 16 which extend at their opposite lateral edges into grooves 17 in the opposed inner faces of the side-members 13, the members 16 being so arranged, as shown, 60 as to cause the slide-proper 10 to present a series of stepped surfaces along which the person slides, this arrangement, in accordance with the embodiment shown, being effected by providing the grooves 17 to extend at angles to the median line of the side-members 13 and in parallel relation to each other the cross-connecting members 14 being located closely adjacent to the lower edges of the members 16. By this arrangement the members 16, when the slide is in normal operating position as shown in Fig. 1, incline downwardly, permitting a person to slide along them by gravity. The platform 11, connected with the slide-frame just described in any suitable manner, is directly supported from the ladder 12 preferably to render the connection a pivotal one. Such connection may be effected in any desirable way, a preferred way, however, being shown 80 in the drawings, wherein a rod 18 passes through depending side-members 19 forming a part of the platform, and through the sides 20 of the ladder 12. By pivoting the ladder to the slide-proper, as stated, the apparatus is rendered foldable at this point to reduce to compact condition for storage. 85

In constructing the apparatus in accordance with the preferred embodiment of my invention, the parts thereof are so arranged 90 that the side-members 20 of the ladder extend upwardly to a considerable distance above the platform 11, as represented in the drawings, this feature being a desirable one in my construction, inasmuch as these upwardly projecting portions of the members 20 furnish a means which may be grasped by one on the platform to steady oneself and prevent falling from the platform. Where the slide-proper and the ladder are pivotally connected together, as, for example, as shown, it is necessary that some means be provided for preventing undue spreading of these parts relative to each other when extended for use, and as a desirable means for 105 this purpose I provide the pivotally jointed strap-sections 21 which are pivotally con- 110

nected at their opposite ends to the sides 20 of the ladder and to the side-member 13, as represented at 22 and 23, respectively, these straps, when the slide-proper and ladder-
5 section 12 are folded together, as shown in Fig. 2, collapsing at their pivotal connections. By preference, the slide-proper is provided with an extension-slide 24, which, in the construction illustrated, is formed of
10 the stepped surfaces 25 and 26, this extension being secured to the lower end of the slide-proper 10, as through the medium of straps 27, one only of which is shown, secured to the sides of the extension 24 and pivoted, as
15 indicated at 28, to depending members 29 on the lower ends of the frame-sides 13. By pivoting the extension 24 to the slide-member it may be folded relative to the latter in the folding of the parts of the apparatus to
20 compact condition, as for storage, as represented in Fig. 2.

The construction illustrated in Figs. 6 and 7 is the same as that shown in the preceding figures, excepting as to the slide-
25 proper. The side-members 13 of the slide-proper are connected together, as explained of the side-members 13 of the other construction, and the same method of securing to these side-members the portion of the
30 slide-proper along which the person slides, and in this case represented at 30, is employed as in the previous construction, namely, the side-members 13 contain grooves into which the opposite edges of the member
35 30 extend, the connecting-members 14 holding the parts in united condition.

While I have illustrated and described two forms in which my invention may be embodied, I do not wish to be understood
40 as intending to limit it thereto, as it may be provided in other forms without departing from the spirit of my invention, it be-

ing my intention to claim my invention as fully and completely as the prior state of the art will permit.

45

What I claim as new and desire to secure by Letters Patent is—

1. In an apparatus of the character set forth, a slide-proper having the surface thereof along which the user slides formed 50 of a series of stepped sections.

2. In an apparatus of the character set forth, a slide-proper formed of side-members spaced apart and each containing a series of grooves along its inner surface, 55 said grooves extending at angles to the median lines of said side-members and in substantially parallel relation with each other, a series of sections fitting at opposite edges in the opposed grooves in said side-members 60 to form a stepped sliding-surface, and means engaging said side-members for holding the latter in spaced relation.

3. In an apparatus of the character set forth, the combination of a slide-proper, a 65 ladder pivoted at its upper end to the upper end of said slide-proper, and an extension-slide pivoted to the lower end of said slide-proper.

4. In an apparatus of the character set 70 forth, the combination of a slide-proper terminating at its upper end in a platform, said slide-proper being formed of a series of sections arranged in stepped relation, and a ladder-section formed of side-members 75 which extend at opposite sides of said platform and project above the latter to form handles to be grasped by the person using the slide, and steps secured to the side-members of said ladder-section, said ladder-section being pivoted at its said side-members 80 to said platform.

THOMAS WALLACE.

Copies of this patent may be obtained for five cents each, by addressing the "Commissioner of Patents, Washington, D. C."
